US0D1103806S

(12) **United States Design Patent** (10) **Patent No.:** **US D1,103,806 S**
(45) **Date of Patent:** **** Dec. 2, 2025**

(54) **SCANNER FRAME**

(71) Applicant: **Evident Canada, Inc.**, Québec (CA)

(72) Inventors: **Benjamin Spay**, Quebec (CA); **Martin Dupuis**, Quebec (CA); **Luis Cooper**, Quebec (CA); **Veronique Simard**, Quebec (CA)

(73) Assignee: **Evident Canada, Inc.**, Québec (CA)

(**) Term: **15 Years**

(21) Appl. No.: **29/755,687**

(22) Filed: **Oct. 22, 2020**

(51) **LOC (15) Cl.** **10-05**

(52) **U.S. Cl.**

USPC **D10/103; D8/61**

(58) **Field of Classification Search**

CLAIM

The ornamental design for a scanner frame, as shown and described.

DESCRIPTION

FIG. 1 is a top-front-left perspective view of a scanner frame, showing our new design;

FIG. 2 is a top-front-right perspective view of the scanner frame;

FIG. 3 is a top-back-right perspective view of the scanner frame;

FIG. 4 is a top-back-left perspective view of the scanner frame;

FIG. 5 is a bottom-front-left perspective view of the scanner frame;

FIG. 6 is a bottom-front-right perspective view of the scanner frame;

FIG. 7 is a bottom-back-right perspective of the scanner frame;

FIG. 8 is a bottom-back-left perspective of the scanner frame;

FIG. 9 is a front view of the scanner frame;

FIG. 10 is a back view of the scanner frame;

FIG. 11 is a right side view of the scanner frame;

FIG. 12 is a left side view of the scanner frame;

FIG. 13 is a top view of the scanner frame; and,

FIG. 14 is a bottom view of the scanner frame.

1 Claim, 13 Drawing Sheets
